(57) CLAIM

We claim the ornamental design for a folding cover assembly, as shown.

DESCRIPTION

FIG. 1 is a perspective view of a folding cover assembly showing our new design;

FIG. 2 is a top plan view thereof;

FIG. 3 is a left side elevational view thereof, which is a mirror image of the right side elevational view thereof; and, FIG. 4 is a rear elevational view thereof and the front elevational view thereof is obstructed by the cab of the pickup truck and is not visible from the front of the pickup truck.
